UNITED STATES PATENT OFFICE.

WINNFIELD RUSSELL PENDER, OF HOUSTON, TEXAS.

FURNACE.

Application filed November 7, 1921. Serial No. 513,503.

To all whom it may concern:

Be it known that I, WINNFIELD R. PENDER, a citizen of the United States, residing at Houston, in the county of Harris and State of Texas, have invented certain new and useful Improvements in Furnaces, of which the following is a specification.

This invention relates to oil furnaces, and it comprises a furnace having a grate formed 10 of fire bricks arranged on suitable supports, the fire bricks being spaced from each other to form openings for the passage of air through the grate, spacing blocks to retain the fire bricks in proper position, dampers 15 arranged beneath some of said openings to permit variation in the amount of air delivered to the furnace, and means for operating said dampers.

An object of the invention is the provision 20 of an oil furnace having a plurality of openings capable of furnishing sufficient air to support combustion of the fuel when the furnace is operated at its maximum capacity, some of said openings being provided with 25 dampers whereby the supply of air may be diminished when the furnace is operated below maximum capacity.

A further object of the invention is the provision of a grate having transverse supports and spacing blocks secured thereto to retain the fire bricks forming the grate in proper position.

A further object is the provision of means 30 for controlling the dampers from the outside 35 of the furnace.

In the accompanying drawings, I have shown one embodiment of the invention. In this showing:

Figure 1 is a horizontal sectional view 40 through a furnace on a line above the grate,

Figure 2 is a vertical longitudinal sectional view on line 2-2 of Figure 1.

Figure 3 is a similar view on line 3-3 of 45 Figure 1,

Figure 4 is a transverse vertical sectional view on line 4-4 of Figure 1,

Figure 5 is a detail view of the grate supporting mechanism, and,

Figure 6 is a detail view of a portion of 50 the damper operating mechanism.

Referring to the drawings, the reference numeral 1 designates the front wall of a furnace and 2 the rear wall. The furnace is provided with side walls 3. Crude oil or other fuel is delivered to the furnace through a pipe 3' extending under the grate and

compressed air or other compressed gas is delivered through a similar pipe 4. The burners may be arranged at the front or back of the furnace, as desired. In the present illustration, I have shown a back shot furnace in which the pipes 3' and 4 communicate with vertical pipes 5 in which the fuel is atomized and delivered therefrom in the form of a spray, indicated at 6.

The grate is supported by means of a longitudinal bar 7, the ends of which are received in the front and rear walls of the furnace. This bar is provided with suitable notches 8 in its upper face, for the reception 70 of transverse supporting bars 9. A plurality of these transverse supporting bars are provided spaced from each other at suitable intervals. The distance between the transverse supporting bars is equal to the width 75 of an ordinary fire brick and the grate is formed of a plurality of fire bricks 10 which are supported on horizontal flanges 11 of the transverse supporting bars. At suitable intervals, the grate is provided with openings 12. Spacing blocks 13 are arranged in these openings and secured to the transverse supporting bars by means of bolts 14. It will be apparent that the use of bolts or other securing means to retain the spacing 80 blocks in position prevents relative movement of the fire bricks and thus insures proper arrangement of the parts forming the grate.

The number of openings 12 is determined 90 by the amount of air necessary to completely burn the fuel when the furnace is operating at its maximum capacity. When operating below maximum capacity, it is desirable to cut down the supply of air in proportion to 95 the reduction in the amount of fuel delivered to the furnace. Certain of the openings 12 are provided with dampers 15 which are pivotally mounted in brackets 16 carried by the transverse supporting members. These 100 dampers may be provided with faces 15', formed of insulating material. These brackets also form bearings for transverse shafts 16'. Levers 17 are keyed to the shaft to revolve therewith. These levers are connected to the dampers by means of links 18. One of the levers is provided with an extension 19 which is connected to a rod or lever 20 extending longitudinally of the furnace and passing through the front wall. As 110 shown, the dampers are arranged in transverse rows and a plurality of them are con-

connected to each of the levers 20. The forward end of each of the levers 20 is connected to a bell-crank lever 21 pivotally mounted in a bracket 22 arranged on the front of the furnace. The other arm of the bell-crank lever is connected to a vertical lever 23. This arm is provided with an extension carrying a counter weight 23'. A plate or bearing 24 is secured to the front of the furnace by means of brackets 25 and a plurality of arms 26, corresponding in number to the levers 20 are journaled in this plate. One end of each arm is provided with a crank portion 27, connected to the vertical levers 23 and the opposite ends are connected to crank portions 28 which are connected to coil springs 29. The ends of the coil springs are secured to a pivoted lever 30, pivotally supported in an arm or bracket 31 mounted on the front of the furnace. The free end of this lever is connected to a control member 32 having a weight 33 on its lower end. This control member is slidably mounted in a bearing 34.

25 The operation of the device is as follows: The dampers are normally held in closed position by counter-weights 23' which force the levers 20 inwardly. When the dampers are to be opened, control member 32 is raised, raising lever 30 and turning the arms 26 to move levers 23 downwardly. This moves the control levers 20 outwardly and opens the dampers. While the dampers are open, the control member 32 may be re-retained in raised position by any suitable means.

40 The construction of the grate is advantageous in that relative movement of the fire bricks is prevented and the openings remain of uniform size at all times. By means of the supports having horizontal flanges, ordinary fire bricks may be employed in the place of specially constructed and relatively expensive bricks or blocks.

45 It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described my invention, I claim:

55 1. A furnace comprising a combustion chamber, a grate arranged below said combustion chamber, said grate comprising a plurality of spaced transverse supporting members, fire bricks arranged thereon, certain of said fire bricks being spaced from each other to provide openings, spacing blocks arranged in said openings and secured to said support-

ing members to maintain said fire bricks in proper position, and dampers controlling said openings.

65 2. A furnace comprising a combustion chamber, a grate arranged beneath said combustion chamber, said grate being provided with openings arranged in series transversely of said furnace, levers extending longitudinally of said furnace, dampers arranged beneath said openings and connected to said levers, said levers projecting through the wall of said furnace, a plurality of arms having crank portions, means for connecting said arms to said levers, and a pivoted control member secured to said arms.

70 3. A furnace comprising a combustion chamber, a grate arranged beneath said combustion chamber, said grate comprising a plurality of transverse supporting members, fire bricks arranged on said supporting members, certain of said fire bricks being spaced from each other to provide openings, dampers to control said openings, said dampers being pivotally mounted on said transverse supporting members, and control levers arranged beneath said grate and connected to said dampers.

75 4. A furnace comprising a combustion chamber, a grate arranged below said combustion chamber, said grate comprising a plurality of spaced transverse supporting members each having horizontal flanges and a vertical flange, fire bricks arranged on said horizontal flanges, the vertical flanges of said supporting members projecting upwardly between said bricks, said fire bricks being spaced from each other to provide openings for the admission of air, and dampers controlling said openings.

80 5. A furnace comprising a combustion chamber, a grate arranged below said combustion chamber, said grate comprising a plurality of spaced transverse supporting members each having horizontal flanges and a vertical flange, fire bricks arranged on said horizontal flanges, the vertical flanges of said supporting members projecting upwardly between said bricks, certain of said bricks being spaced from each other to provide openings, a pair of spacing blocks mounted in each of said openings at each side thereof and secured to the vertical flanges of said supporting members to maintain said fire bricks in proper position, and dampers controlling said openings.

85 In testimony whereof I affix my signature in presence of two witnesses.

WINNFIELD RUSSELL PENDER.
